UNITED STATES PATENT OFFICE.

FRITZ BALZER, OF CHICAGO, ILLINOIS, ASSIGNOR TO TROY LAUNDRY MACHINERY COMPANY, LIMITED, OF CHICAGO, ILLINOIS, A CORPORATION OF NEW YORK.

SAFETY MECHANISM FOR ELECTRICALLY-OPERATED EXTRACTORS.

1,236,530.

Specification of Letters Patent.

Patented Aug. 14, 1917.

Application filed December 22, 1913, Serial No. 808,268. Renewed January 18, 1917. Serial No. 143,185.

To all whom it may concern:

Be it known that I, FRITZ BALZER, a subject of the Emperor of Germany, residing at Chicago, in the county of Cook and State 5 of Illinois, have invented certain new and useful Improvements in Safety Mechanism for Electrically-Operated Extractors, of which the following is a specification.

My invention relates in general to safety 10 mechanism for controlling the operation of electrically actuated machines, and more particularly to electrically driven centrifugal extractors.

The high speed at which the baskets of 15 centrifugal extractors are rotated renders their use dangerous to careless operators, unless such extractors are provided with safety appliances for permitting the application of power to rotate the baskets only 20 when the protecting covers are closed, and for preventing the opening of the covers while the baskets are rotating.

The primary object of my invention is to 25 provide an electrically driven machine having a protecting cover for the moving element, with a shield to permit access to the starting switch only when the cover is in protecting position.

A further object of my invention is to 30 provide an electrically driven machine with safety mechanism for permitting the starting of the motor only when the moving element of the machine is protected, and for preventing access to the moving element 35 during the continuation of its movement.

A further object of my invention is to 40 provide an electrically driven centrifugal extractor having a cover for preventing access to the revolving basket, in which the motor circuit can only be closed when the 45 cover is closed, and in which the driving means which necessarily rotates while the basket rotates will be so connected with the cover that it can not be opened until such driving means have ceased to move.

Still another object of my invention is to 50 provide a centrifugal extractor which will be simple in construction and operation, and the use of which will be free from danger to the operators.

My invention will be more fully disclosed hereinafter with reference to the accompanying drawings in which the same is illus-

trated as embodied in a convenient and practical form, and in which—

Figure 1 is a side elevational view;

Fig. 2 is a detail view;

Fig. 3 a rear elevational view of the casing with the safety mechanism thereon; and

Fig. 4 a diagrammatic view of the circuit of the electric motor.

Similar reference characters are used to designate similar parts in the several figures of the drawings.

Reference letter A indicates the casing of 65 a centrifugal extractor in which is inclosed the usual revolving basket, not shown. B designates a suitable support for the casing A comprising standards and a base b adapted to be supported upon the floor. C designates a cover for closing the top of the casing, thereby preventing access to the inclosed basket. D designates a vertical spindle upon the upper end of which the basket is supported and to which power is applied for 70 75 rotating the same and thereby imparting revolution to the basket. d designates a pulley secured concentrically around the spindle D which is engaged by a driving belt E.

F designates one of a pair of idler pulleys 80 around which the belt E passes and by which it is guided to the pulley d. The belt E passes around a pulley g driven by an electric motor G, the latter being suitably supported on a standard H connected by a brace 85 H' with the casing A and by means of a bolt h' with the base b of the support for the casing. The standard H is provided with a lateral extension h upon which are supported the pair of idler pulleys around 90 which the belt E passes.

K designates a switch for controlling the motor circuit and is preferably mounted directly upon the exterior of the casing A. The switch comprises push-buttons K' and 95 K² for starting and stopping the motor. While the arrangement of the circuit of the motor G does not in itself constitute my invention, I have illustrated in Fig. 4 diagrammatically a convenient arrangement of 100 the motor circuit in which the push-buttons K' and K² are shown as controlling circuits leading to a starting switch mechanism G² which controls a circuit from the lines through the armature G', the series field g' 105 and the shunt field g² of the motor. L des-

ignates a guard mounted upon the controlling switch K and movable relatively to the push-buttons K' and K². The guard L is provided with holes therethrough L' and L² which in one position of the guard overlie the push-buttons and permit access to them, but in another position of the guard the said openings do not align with the push-button and hence access to them is prevented. The guard L is provided with a flange l at one end thereof which is secured to the outwardly projecting end of a reciprocating rod m suitably mounted upon the exterior of the casing A as by means of the guide tube M. The opposite end of the rod m to that which is connected to the guard is pivotally connected to one arm of the bell crank lever M' mounted to oscillate at m' upon the casing. The other end of the bell crank lever is pivotally connected to the lower end of the rod n, the upper end of said rod being pivotally connected to an arm n' of the bell crank lever N journaled between a pair of ears o on a bracket O secured to the rear outer surface of the water guard a'. The other arm n² of the bell crank lever N is pivotally connected to a link P which extends through an opening in the water guard a' and is pivotally connected at p to the cover C, the said point of pivotal connection p being located adjacent but eccentric to the hinge of the cover C.

When the cover C is in its closed position, so as to prevent access to the basket within the casing A, the guard L is in such position relatively to the push-buttons that the holes L', L² overlie the push-buttons and permit them to be actuated. The circuit to the starting switch mechanism G² may consequently be closed so as to start the motor and consequently rotate the basket through the medium of the belt E and engaged pulleys. When the cover C is lifted to its open position, shown in dotted lines in Fig. 1, the link P is moved toward the right, thereby oscillating the bell crank lever N so as to depress the rod n and thereby oscillate the bell crank lever M' in a direction to move the rod m and with it the guard L toward the left to such a position that the holes L' and L² in the guard are moved out of registry with the push-buttons, thereby preventing access to the push-buttons to start the motor. The motor cannot be started, and hence the basket cannot be rotated, while the cover is open.

While the above described mechanism prevents the starting of the motor until after the cover has been closed, yet it does not in itself prevent the lifting of the cover after the motor has been started, and hence if no co-operating safety mechanism were employed it would be possible for a careless operator to lift the cover while the basket continued to be driven, and thereby render

possible an accident owing to the exposed condition of the rapidly revolving basket. In order to avoid such a possibility, I provide mechanism for preventing the raising of the cover during the rotation of the basket, which, in co-operation with the mechanism above described for preventing the starting of the motor until after the cover has been closed, renders the extractor entirely safe under all conditions. The safety mechanism for preventing the lifting of the cover during the rotation of the basket which I have illustrated in connection with my improved means for preventing the starting of the motor, except when the cover is closed, is the safety mechanism covered by the patent granted jointly to William Bartholomew, James F. Broderick and myself, No. 1,120,388, December 8, 1914, which may be briefly described as follows:

A bell crank lever R is fulcrumed at r upon the rear outer surface of the water guard a' and is connected to a bolt r which is mounted to reciprocate through aligned openings in a pair of ears o' mounted on the bracket O between which the link P reciprocates. The link P is provided with a hole which when the cover is closed aligns with the path of movement of the bolt r so that the latter then extends through the hole in the link and prevents the rearward movement thereof necessary to the opening of the cover C. A spring r² is connected with the bell crank lever R to normally oscillate the same in position to project the bolt r through the hole in the link P. The shorter arm of the bell crank lever R is pivotally connected to a rod S, the lower end of which is connected to a detent s fulcrumed at S' adjacent the spokes of the pulley F, which are provided with lugs f having a path of movement so close to the end of the detent s that the latter cannot be moved in a direction to permit the withdrawal of the bolt r from engagement with the link P during the rotation of the pulley F. A weight s' is connected to the detent s so as to normally oscillate the detent to a position out of the path of the lugs f on the spokes of the pulley F, in a manner fully disclosed in the said prior Patent No. 1,120,388.

From the foregoing description it will be observed that I have invented improved safety mechanism for electrically driven machines, and particularly for centrifugal extractors, by means of which the motor cannot be started unless the safety cover is in position to protect the moving member, and in which the safety cover cannot be removed from its protecting position while the moving member continues to move.

I claim:

1. The combination with a machine comprising a driven element, of a movable guard for protecting said element, an electric mo-

- tor for driving said element, a switch for controlling the circuit of said motor, and means for preventing the operation of said switch when the guard is out of protecting position relatively to said element.
- 5 2. In a centrifugal extractor, the combination with a casing, of a rotary basket in said casing, a cover for said casing, an electric motor for rotating said basket, and means for preventing the starting of said motor when said cover is open.
- 10 3. In a centrifugal extractor, the combination with a casing, of a rotary basket in said casing, a cover for said casing, an electric motor operatively connected to said basket to rotate the same, a switch controlling the circuit of said motor, and means for preventing access to said switch when said cover is open.
- 15 4. In a centrifugal extractor, the combination with a casing, of a rotary basket in said casing, a cover for said casing, an electric motor operatively connected to said basket to rotate the same, a switch controlling the circuit of said motor, a guard movable relatively to said switch, and means operated by said cover to move said guard into position to prevent the operation of said switch when the cover is opened.
- 20 5. In a centrifugal extractor, the combination with a casing, of a rotary basket in said casing, a cover pivotally mounted on said casing, an electric motor operatively connected to said basket to rotate the same, a switch controlling the circuit of said motor, a guard movable relatively to said switch, and means operated by said cover to move said guard into position to prevent the operation of said switch when the cover is opened.
- 25 6. In a centrifugal extractor, the combination with a casing, of a rotary basket in said casing, a cover pivotally mounted on said casing, an electric motor operatively connected to said basket to rotate the same, a switch controlling the circuit of said motor, a guard movable relatively to said switch, and means operated by said cover to move said guard into position to prevent the operation of said switch when the cover is opened.
- 30 7. In a centrifugal extractor, the combination with a casing, of a rotary basket in said casing, a cover pivotally mounted on said casing, an electric motor operatively connected to said basket to rotate the same, a switch controlling the circuit of said motor, a guard movable relatively to said switch, and means operated by said cover to move said guard into position to prevent the operation of said switch when the cover is opened.
- 35 8. In a centrifugal extractor, the combination with a casing, of a rotary basket in said casing, a cover for said casing, an electric motor for rotating said basket, means for preventing the starting of said motor when said cover is open, and means for preventing the opening of said cover during the rotation of said basket.
- 40 9. In a centrifugal extractor, the combination with a casing, of a rotary basket in said casing, a cover pivotally mounted on said casing, an electric motor operatively connected to said basket to rotate the same, a switch controlling the circuit of said motor, a link pivotally connected to said cover and reciprocated thereby, a guard movable relatively to said switch, means connecting said link with said guard to move the same into position to prevent the operation of said switch when the cover is opened, a lock for engaging said link to prevent the movement thereof necessary to the opening of said cover, and means for automatically retaining said lock in engagement with said link during the rotation of said basket.
- 45 10. In a centrifugal extractor, the combination with a casing, of a rotary basket in said casing, a cover pivotally mounted upon said casing, an electric motor, power transmitting connections from said motor to said basket, a switch mounted upon said casing for controlling the circuit of said motor, a guard movable relatively to said switch, a link pivotally connected to said cover and reciprocated by the opening and closing movements thereof, means connecting said link with said guard to move the same into position to prevent the operation of said switch when the cover is opened, a lock engaging said link to prevent the movement thereof necessary to the opening of said cover, and means operated by the movement of said power transmitting connections for automatically retaining said lock in engagement with said link during the rotation of said basket.
- 50 11. In a centrifugal extractor, the combination with a casing, of a rotary basket in said casing, a cover pivotally mounted on said casing, an electric motor operatively connected to said basket to rotate the same, a switch mounted on said casing for controlling the circuit of said motor, a guard mounted upon said casing to reciprocate relatively to said switch, a bell-crank lever fulcrumed upon said casing, a rod connecting one end of said bell-crank lever to said guard, and means connecting the other end of said bell-crank lever to said cover, whereby when the cover is opened said guard is moved into position to prevent access to said switch.
- 55 12. In a centrifugal extractor, the combination with a casing, of a rotary basket in said casing, a cover pivotally mounted on said casing, an electric motor operatively connected to said basket to rotate the same,

4
a push button switch for controlling the circuit or said motor, a plate mounted to reciprocate relatively to said switch and having a hole therethrough adapted to register with the push-button, and means connecting said plate with said cover to move said plate into position for the hole therethrough to register with the push button when the cover is closed, and to move said plate into a posi-

tion where the hole therethrough is out of registry with said push button when the cover is opened.

In testimony whereof, I have subscribed my name.

FRITZ BALZER.
